J. R. Scifield of Lisle, N.Y.
Letter Patent No. 1775, dated Jan. 16, 1863.

The schedule referred to in these Letters Patent and making part of the same.

To all whom it may concern:

Be it known that I, J. R. Scifield of Lisle, in the County of Bronx, and State of New York, have invented a new and ornamental Design for Touching the Laws of Discordant and Harmonious Colors, and I do hereby declare that the following is a full, clear, and exact description of the same, reference being had to the accompanying drawing forming a part of this specification.

The drawing represents a plan or top view of my design.

This design consists of a star composed of six diamond shaped panels, which are colored red, orange, yellow, green, blue, and violet and arranged in the center of radiating segments colored in such a manner that the color in each segment is complementary to its opposite, and that each of the diamond shaped panels projects into that segment the color of which is complementary to that of the segment, and by these means an effect is produced which cannot be produced by any other juxtaposition of colors.

To enable others skilled in the art to fully understand and construct my invention, I will proceed to describe it with reference to the drawing.

A, represents a star composed of six diamond shaped panels a. which are colored red, orange, yellow, green, blue, and violet, thus representing the three primary colors red, yellow and blue, and between them the three secondary colors orange, green and violet. The red panel is opposite to its complementary green, the yellow opposite its complementary violet, and the blue opposite to its complementary orange.

This star is placed on the center of a series of radiating segments B, which are colored with the primary, secondary and intervening colors, which are so arranged in relation to each other that each stands exactly opposite to its complementary color. At the same time each of the diamond shaped panels a. of the star A projects into that one of the

354

Dec. 1775

segments, the color of which is complementary to the color of said panel viz: the red panel projects into the green segments, the orange into the blue, the yellow into the violet, the green into the red, the blue into the orange, and the violet into the yellow.

By this arrangement of the colors of the star in relation to each other and to the colors of the segments an effect is produced which can not be equaled by any other juxtaposition of colors.

Having thus fully described my design, what I claim as new and desire to secure by Letters Patent, is

The star A, composed of six diamond shaped panels a. colored red, orange, yellow, green, blue, and violet and placed in the centre of a series of radiating segments B, colored in the manner herein shown and having the colors arranged in relation to each other as specified.
